[57] CLAIM

The ornamental design for a brace for a folding chair, as shown and described.

DESCRIPTION

FIG. 1 is a perspective view of the brace for a folding chair embodying the design of the present invention;
FIG. 2 is a front elevational view thereof;
FIG. 3 is a typical side elevational view thereof, the side opposite being a mirror image of the side shown in FIG. 3;

FIG. 4 is a rear elevational view thereof;

FIG. 5 is a top plan view thereof;

FIG. 6 is a bottom view thereof; and,

FIG. 7 is a perspective view of a chair having the folding chair brace thereon, with the chair being shown in broken lines for illustrative purposes only.

FIG. 2.

FIG. 1.

FIG. 4.

FIG. 3.

FIG. 6

FIG. 5.
